UNITED STATES PATENT OFFICE.

FREDERIC HENRY BULLINGER, OF YONKERS, NEW YORK, ASSIGNOR TO WARD
LEONARD ELECTRIC COMPANY, A CORPORATION OF NEW YORK.

ELECTRIC CONTROLLER.

Application filed July 29, 1921. Serial No. 488,285.

To all whom it may concern:

Be it known that I, FREDERIC H. BULLINGER, a citizen of the United States, residing at Yonkers, in the county of Westchester and State of New York, have invented certain new and useful Improvements in Electric Controllers, of which the following is a specification.

This invention relates particularly to electric controlling means for an isolated plant or farm equipment comprising a gas engine, a storage battery, a charging dynamo also used as a motor for starting the gas engine, and the whole being adapted for supplying light and power. The controlling means of this invention controls the various circuits for operating the dynamo as a motor for starting the engine, also controls the ignition circuit of the engine and likewise provides automatic means for closing the charging circuit when the dynamo has attained proper voltage, provides for the automatic opening of the charging circuit when the voltage of the dynamo becomes too low, or upon the passage of a reverse current, and also provides a no-voltage ignition release for making the ignition circuit ineffective upon the occurrence of no voltage.

The main object of my invention is to provide controlling means of the above character which will insure proper sequence of control and proper operation of the parts without any dependence upon the skill of the operator and provide a construction which will stand rough usage, be well enclosed and protected so as to avoid tampering with the device, and small in size and compact and durable in construction and effective in operation and in the proper making and breaking of the circuits at the contacts. Another object is to provide a single controlling element for operation by the user so as to make its use convenient and simple, moving the single controlling element in one direction for starting and in the opposite direction for stopping.

Another particular object is to insure the proper control of the ignition circuit during starting and the maintenance of the ignition circuit in proper condition for operation as long as proper ignition voltage is available, but to cause the ignition circuit to be rendered ineffective automatically upon failure or lack of proper voltage.

Another object is to so relate all of the

parts to each other that they are well adapted to effectively co-operate with certainty of operation in proper sequence and relationship; and to also so form the elements of the device and their relationship to each other that they may be easily formed or stamped out from sheet material and conveniently and quickly assembled with minimum cost of labor and material.

These and other objects and advantages of my invention will be more fully understood by those skilled in the art from the following description and accompanying drawings, which illustrate a preferred embodiment of my invention.

Fig. 1 is a front elevation of my improved electric controlling means; Fig. 2 is a front elevation of the apparatus with the cover and controlling magnet and certain other parts removed; Fig. 3 is a side view of the parts shown in Fig. 2; Fig. 4 is a side view of the controlling magnet and automatic cutout switch with some parts in section; Fig. 5 is a rear view of the cover and automatic cutout switch; Fig. 6 is a vertical section on the line 6—6 of Fig. 2; Fig. 7 is a side view of the snap switch in closed position; Fig. 8 is a side view of the snap switch in the position at which it is about to snap to closed position; Fig. 9 is a diagram of connections, and Fig. 10 is a diagram of connections showing the adaptation of my improvement to the control of differently arranged circuits.

Referring to Figs. 2 and 3, the base 1 is composed of a sheet metal plate having its side edges bent backwardly and forwardly so as to form vertical grooves 1^a and forwardly extending edges 1^b. At the upper end of the base plate is a forwardly extending part 1^c bent at right angles to the base plate, and also having a downwardly extending edge 1^d with holes by which the cover may be secured by means of rivets. The lower end of the base plate has a portion 1^e bent at right angles to the base plate and also has perforated ears 1^f bent at right angles to the part 1^e by means of which the cover may be riveted to the base. The portion 1^e of the base also has a rounded extension 1^g on each corner which extends upwardly. A thin strip of sheet metal 2 bent in the form of the letter U closes the sides and top of the device by being slid down from the top in the grooves 1^a and secured

to the parts 1^a of the base by screws 2^a as shown in Fig. 2. A cover 3 of brass or other non-magnetic material having inwardly turned edges, embraces the front edges of the portions of the base above referred to and also the front edge of the U-shaped piece 2, and is secured in place by preferably being riveted to the portions 1^a and 1^b of the base.

10 A sheet 4 of insulating material covers the front of the upper half of the base plate and a similar sheet 4^a covers the rear of the upper half of the base plate. On the insulation 4 are mounted four flat terminal blocks 5, 5^a, 15 5^b and 5^c; and mounted directly on the base plate below the insulation 4 is another terminal block 5^d. These terminal strips or blocks have terminal screws 6 secured thereto and extending through the base plate 20 to afford means for connection of the parts in circuit at the rear of the apparatus. Under the terminal 5^b is a flat copper strip 7 which is in electrical connection with the terminal 5^d and has a lower forwardly turned 25 edge 7^a extending at an angle of about 45° to the base. The plate 7 forms the fixed contact of the main circuit for starting purposes.

The movable portion of the main switch 30 or starting switch, and its method of co-operating with the fixed contact will now be described (see particularly Figs. 2, 3, 7 and 8). A strip 8 of sheet metal extends along the lower portion of the base plate and is 35 riveted thereto or otherwise suitably secured. From the upper left-hand corner of the strip 8, an extension extends upwardly and carries two forwardly extending ears 8^a bent at right angles to the base plate, thus forming 40 a trough for the reception and support of the movable portions of the snap switch. The side portions 8^a have a specially formed cam shaped periphery, shown in Fig. 3. A pin 9 is supported by and extends through the ears 45 8^a, and has its left-hand end of reduced diameter and riveted over the outside portion 8^a, thus simply and securely fixing the pin 9 in position. Between the portions 8^a and pivotally mounted upon the pin 9 is a 50 sheet metal element 10 of U-shape. The sides of the element 10 extend downwardly and forwardly and each side carries a projection 10^a bent at right angles to the side portions and extending outwardly therefrom. The 55 right-hand portion of the element 10 carries an extension 10^b, the lower end of which has a part 10^c bent at right angles to the part 10^b and curved slightly so as to present a rounded lower surface. The inner end of the portion 10^c engages the plate 8 when in normal 60 position and serves as a stop for the parts when the switch is open.

Another U-shaped element 11, also formed of sheet metal has its sides embracing the 65 sides of the pivoted element 10 and is piv-

oted to the element 10 by means of the projections 10^a which pass loosely through holes in the side portions of the element 11. Each of the side portions of the element 11 has an inwardly extending projection 11^a as shown 70 in Figs. 3, 7 and 8. These projections 11^a engage the periphery of the side portions 8^a and are adapted to travel along this periphery during the closing movement of the switch when the element 10 is turned upon its pivot to close the switch, giving a peculiar compound movement of the parts as below described. The upper portion of the U-shaped element 11 connects the two sides thereof and carries a screw 11^b which engages and secures to the element 11 the movable contact 12. This contact is shown as a copper strip having two portions at right angles to each other, one of these portions 80 extending under the upper end of the U-shaped element 11 and being permanently secured thereto by the screw 11^b.

A retracting spring 13 is secured at one end to the inner end of the screw 11^b and at the other end to the outer end of a post 8^b, 90 which is formed by an extension of the sheet metal strip 8 being bent at right angles to the base.

The operating element of the device, or in other words, the manually moved element, is 95 shown as a square post 14 pivotally mounted at its inner end on the strip 8 and base plate. The element 14 extends forwardly and passes through the cover 3 and has fixed thereto a wing-nut 14^a at its outer end. A sheet metal strip 15 embraces two sides of the element 14 as shown in Fig. 2 and is riveted or otherwise secured thereto, and has an extension 15^a extending to the left and is adapted to engage the outer rounded surface of the portion 10^c of the pivoted element 10 so that when the element 14 is turned in a clockwise direction, the part 15^a will push against the portion 10^c of the element 10 and cause the same to be turned about the pin 9. 110

The snap switch is shown in open position in Figs. 2 and 3 and it will be seen that the line of action of the spring 13 is in front of the pivot point of the element 11 and also of the element 10. To close the switch, the element 14 is turned about 45° in a clockwise direction, which causes the element 10 to be turned upon the pin 9 as aforesaid. In this movement the element 11 is necessarily carried upwardly against the pressure of the spring by reason of its pivotal connection with the element 10. But during this movement the projections 11^a of the element 11 are caused to slide along the peripheries of the portions 8^a, being held in engagement therewith by the pressure of the spring 13. The result is that as the closing movement continues, and the pivotal support of the element 11 approaches the line of action of the spring, the engagement of the projections 125 130 135

11^a on the portions 8^a will cause the element 11 to be turned on its pivotal connection with the element 10 and so cause the upper end of the element 11 to be moved inwardly 5 and thus cause the upper end of the spring to also be moved inwardly and the line of action of the spring to be thrown past the pivotal support of the element 11 on the element 10. This causes the switch to be 10 suddenly snapped to the closed position shown in Fig. 7, and as the line of action of the spring is carried a considerable distance within the pivotal support of the element 11 before the contacts are actually engaged, it 15 results in the switch being closed with a considerable blow and in a firm contact being made at the upper or flat portion of the fixed contact 7 to establish the circuit.

The operator holds the wing-nut 14^a in 20 its deflected position after the switch is closed, as long as necessary for causing the dynamo acting as a motor to start the engine, and as soon as the engine starts, the operator releases the wing-nut 14^a. But the 25 construction is such that whether the operator quickly or very slowly releases the wing-nut, an effective and sudden breaking of the circuit by the snap switch is insured, and there is no intermediate point of uncertain 30 contact before the circuit is effectively broken. Considering the parts in the position shown in Fig. 7, it will be seen that when the operator releases the wing-nut, the spring 13 will draw the movable contact 35 down across the surface of the fixed contact 7 until it engages the bent portion 7^a. With this downward movement, the element 10 is being turned about its pivot and the element 11 is also being turned about its pivot permitting 40 the spring to firmly hold the movable contact against the fixed contact in its downward travel. When the movable contact engages the bent edge 7^a, the spring continues 45 to draw the movable contact firmly against its surface and to draw the movable contact over the inclined surface. As the line of action of the spring approaches the axis of the pivotal support of the element 11, the movement of the movable contact over 50 the inclined surface 7^a causes the upper end of the element 11 to be shifted outwardly and as this carries the outer end of the spring outwardly also, the result is that the line of action of the spring is suddenly thrown 55 past the axis of the element 11. This causes the spring to quickly throw the movable contact from engagement with the inclined surface of the fixed contact giving an abrupt break with a minimum amount of arcing. 60 This rapid and firm closure of the contacts secures a firm engagement, and together with the sliding action of the movable contact over the face of the fixed contact, and the abrupt break of the contacts as above described at a different surface than that at

which the closing of the contacts is made, insures keeping the contacts clean and in good operating condition without material deterioration with continued use and also insures an effective closing and opening of 70 the switch.

The automatic switch for closing and opening the charging circuit between the dynamo and the battery is mounted upon and carried by the cover plate 3 (see Figs. 4 and 75 5). It comprises magnet 16 made up of stamped sheets riveted together to form the necessary thickness and in this instance is shown E-shaped having a central leg 16^a, an upper leg 16^b and a lower leg 16^c. The central leg carries a shunt winding 17 surrounded by a series winding 18, the windings being separated from the cover by a sheet 19 of insulating material. The four leads from 80 these windings pass through holes in the cover plate and are soldered or otherwise suitably connected to the terminals or contacts as hereinafter described. The inner ends of the magnet pass through the cover plate as shown in Fig. 4, the outer legs being 90 notched to engage the outer surface of the cover.

The armature 20 is in the form of a flat strip of sheet iron or steel and is pivotally supported at its lower end by a thin strip 21 of phosphor bronze or other suitable material. This strip is clamped to the inner lower end of the armature by a sheet metal piece 22 which has projecting extensions engaging the edges and face of the lower end of the armature. Another sheet metal element 23 is bent around the inner end of the leg 16^c of the magnet and has supporting portions 23' bent at right angles and engaging the inner face of the cover plate. 100 The phosphor bronze strip 21 passes under the central portion of the strip 23; and on the inner face of the end of the phosphor bronze strip is another sheet metal rectangular piece 24 having projections 24' which pass through holes in the strip 23, the projections 24' being bent over the face of the strip 23 and thereby securely clamping the hinging strip to the element 23. The element 23 also has projections 23^a and 23^b, 110 which are bent to extend away from the element 23, and serve to carry the retracting spring 24^a of the armature. The spring 24^a is in the form of a wire and is fulcrumed in a notch in the element 23^a, the outer end of the wire being placed under a hook formed in the element 23^b. The elements 23^a and 23^b are bendable by means of pliers so as to 115 adjust the tension of the spring 24^a to the exact amount required and serve to give a permanent adjustment. The upper end of the spring 24^a is hooked to the upper end of the armature 20 by being passed through holes therein. The screws 25 pass through 120 the extensions 23' and through the cover 125 130

plate and engage a sheet metal strip 26 on the face of the cover. The element 26 engages a notch in the leg 16^a of the magnet so that the screws 25 serve not only to hold the element 23 and parts carried thereby in fixed position, but also by means of the plate 26 serves to clamp the lower leg of the magnet firmly against the cover plate.

The upper end of the armature 20 has 10 fixed thereto the movable contact 27 which is shown in the form of a sheet metal copper strip which has soldered thereto a lead 27'. The fixed contact 28 is also in the form of a sheet metal copper element bent into position 15 to receive the movable contact 27 when the armature of the magnet is attracted. The fixed contact 28 has extensions 28' which are embraced and supported on opposite sides by insulating strips 29. A metal strip 30 20 extends along the upper face of the upper insulating strip 29 and receives screws 31 by which the fixed contacts and insulating parts are supported on a sheet metal supporting strip 32. This sheet metal element 32 has its 25 main portion engaging the inner face of the cover plate and has extensions bent at right angles to receive the screws 31. The element 32 also has the extension which receives one of the screws 31 extended to form a projection 32^a, which extends over the end of the armature 20 and serves as a back-stop to limit its retracted position. This extension 32^a is bendable so that the outer position of the armature may be adjusted to the exact 35 position required and will of course retain its adjustment permanently. On the face of the cover plate is a sheet metal strip 33 which engages a notch in the upper leg 16^b of the magnet. The screws 34 pass through 40 the element 32 and through the cover plate and engage the cross piece 33 and thus securely fasten the fixed contact of the magnet and the stop for the armature in position on the back of the cover, and likewise securely clamp the upper end of the magnet against the cover plate by reason of the strip 33 engaging the notch in the magnet and drawing the magnet down so that it firmly engages the cover plate at the upper notched 45 portion of the magnet.

The ignition circuit controlling means and the automatic no-voltage release thereof (see particularly Figs. 2, 3 and 6) is functionally related to the manually operated element 14 55 and to the electro-magnet already described. The contact block 5^c is connected to the ignition supply circuit, and has a forwardly bent edge 35 on which is pivotally mounted a sheet metal element 36. The element 36 60 is L-shaped and has one leg 36^a serving as a stop to limit one position of this element by engaging the insulating sheet 4. This leg 36^a has a notch which is engaged by one end of a spring 37 which passes around the pivot 65 of the element 36 and has one end 37^a engag-

ing the insulating sheet 4, whereby this spring 37 normally tends to hold the contact element 36 so that the leg 36^a engages the insulating sheet 4. The other leg 36^b of the element 36 extends forwardly and has an end 70 36^c bent at right angles thereto to form a contacting surface for the ignition supply circuit.

The sheet metal element 8 at the right-hand end thereof has an upwardly extending 75 portion 8^b to which is pivotally connected a sheet metal element 38. This element has a portion 38^a engaging the extension 8^b and pivotally supported thereon. From the portion 38^a extends at right angles thereto a 80 part 38^b which has an extension to the left which engages the pin 9 to serve as a stop. Upwardly from the part 38^b and at right angles thereto the element 38 continues and 85 at its upper end carries a contact pin 38^c which is adapted to engage the contact face 36^c of the element 36. Bent at right angles to the upper end of the element 38 is another 90 extending portion 38^d, which extends inwardly toward the middle leg 16^a of the controlling magnet.

From the portion 38^a of the element 38 a 95 projection 38^e extends in the direction of the operating element 14. The sheet metal element 15 carried by the element 14 has an upwardly extending portion 15^b and a part 15^c 100 at right angles thereto. A spring 39 in the form of a wire has one end engaging a hole in the portion 38^b of the element 38 as shown in Fig. 2, and passes above the pivotal axis of the element 38 and downwardly to the right and has its lower end fixed to the element 8. For this purpose the right-hand end of the element 8 is provided with forwardly 105 extending projections 8^e and 8^f with a slot 110 between them. The wire 39 passes through this slot and enters a hole in the projection 8^a and thereby supports the lower end of the wire spring 39. The projections 8^e and 115 8^f are bendable so that the tension imposed on the element 38 by the spring 39 may be properly and permanently adjusted.

In operation when the manual element 14 is turned clockwise by the wing-nut, the 115 portion 15^b carried by the element 14 engages the end of the extension 38^e and thereby turns the element 38 counter-clockwise on its pivot. This causes the upper contacting portion of the element 38 to engage the contacting face 36^c of the element 36 closing 120 ignition supply circuit, and as the movement is continued, the element 36 is turned on its pivot against the action of spring 37 and the contact with the element 38 is maintained. This movement also carries the part 38^d of 125 the element 38 which is of soft iron or steel, near the inner end of the leg 16^a of the magnet; and if the magnet is sufficiently and properly energized, it will retain the element 38 in the position to which it has been forced 130

by the operator, and thus maintain the ignition circuit. But if there is not sufficient voltage or if the voltage should drop at any time below a minimum limit, the magnet 5 will no longer hold the element 38 in its retracted position, and the spring 39 will then carry the element 38 to the right and break the ignition circuit connection with the element 36. When the element 38 is retracted 10 by its spring, the extension from the portion 38^b engages the pin 9 and serves as a stop for the element 38 after connection has been broken with the element 36.

If during normal operation of the apparatus, it be desired to stop the engine, the wing-nut 14 is merely turned slightly in a counter-clockwise direction and the element 38 is thereby forcibly thrown from the position in which it is held by the magnet, and 15 so causes the interruption of the ignition circuit. This action is due to the fact that when the element 14 is turned counter-clockwise, the extension 15^b engages the left-hand end of the portion 38^b and thereby causes the element 38 to be turned in a clockwise direction about its pivot and so interrupt the ignition circuit. The part 15^c is provided to 20 serve as a stop for the element 14 when turned counter-clockwise, the movement being limited by the portion 15^c engaging the right-hand portion 8^a of the element 8.

In starting it will be apparent that the element 14 not only serves to close the snap switch but it likewise serves to close the 25 ignition supply circuit in the manner already described and the parts are so related and proportioned that the ignition supply circuit is closed before the snap switch is closed and is maintained closed by the magnet even after the operator releases the element 14 and after the snap switch has 30 opened.

The electrical connections of the parts already described are shown in Fig. 9, where 35 corresponding parts are similarly numbered. The storage battery is indicated at 40, the gas engine at 42, and the dynamo armature 41 is shown as having a shunt field winding 41^a and a series field winding 41^b. The contact 5^d being mounted upon the base plate 40 forms the ground of the system and is electrically connected with one terminal of the battery. The element 38 is obviously in electrical connection with the contact 5^d and 45 when moved as above described by turning of the manual element in a clockwise direction, will cause the ignition supply circuit to be closed, a lead extending from the terminal 5^c to the ignition means. The movable 50 contact 12 carried by the element 11 is electrically connected by a heavy flexible lead with the terminal 5^d and when the snap switch is closed to operate the dynamo as a motor for starting the engine, the circuit is 55 completed from the snap switch through the

terminal block 5^d and by an external connection the circuit continues through the series field 41^b of the dynamo, thence through the armature 41 to the other terminal of the battery. The battery will thus supply a current to operate the dynamo as a series motor for starting the engine, the ignition circuit having previously been closed as already 70 described. After the engine indicated at 42 has been started, the operator releases the wing-nut 14^a and the engine then operates the dynamo as a shunt wound generator to supply charging current to the battery. This charging circuit is controlled by the 75 electromagnetic switch already described. 80 The shunt winding 17 of the magnet has its lead connected to the terminal blocks 5, 5^a; and rear connections extend therefrom to the respective terminals of the dynamo. The series winding 18 has one lead connected to the fixed contact 28 and the other lead connected to the terminal block 5^a. It will be seen that when the dynamo acting as a generator has attained proper voltage, the shunt winding 17 being subjected thereto, will 85 cause the armature 20 to be attracted and cause the movable contact carried by the armature 20 to engage the fixed contact 28 and close the circuit through the battery and dynamo armature for charging purposes. 90

If the voltage of the dynamo falls below a predetermined minimum, or a reverse current flows from the battery through the series winding 18, the circuit between the 100 battery and charging dynamo will be automatically opened to protect the battery; and likewise at a predetermined minimum or upon the occurrence of no voltage, the interruption of the ignition circuit will automatically occur by release of the element 38, 105 as already described. If during normal operation, the manual element be turned counter-clockwise the ignition supply will be interrupted as already described, causing the 110 gas engine to stop, whereupon the armature 20 will be released by the magnet automatically, and the circuit between the dynamo and storage battery will be automatically 115 opened to protect the battery from discharge.

Although one form of my invention is illustrated in the accompanying drawings, and one form of connections shown in Fig. 9, my improved controlling means is adapted 120 for various uses and various arrangements of circuit connections and may be modified in construction and relationship of parts without departing from the scope of my invention.

In Fig. 10, the parts are similarly numbered, but the series field winding 41^b of the dynamo is differently connected. In this instance, one lead from the series field winding is connected to the terminal block 5^a and one 125 of the armature terminals is connected to 130

this terminal block through the series field winding, another lead from the same armature terminal passing directly to the terminal 5°. In this instance, the dynamo will 5 operate as a shunt wound motor to start the gas engine by the closure of the snap switch; but the dynamo will operate as a compound wound generator to charge the battery after the gas engine has been started and the snap 10 switch opened.

Although I have shown a construction whereby the ignition supply circuit is closed during normal operation, yet in some cases it may be preferred to cause the element 36 15

15 to engage a fixed contact when the system is not in operation and thus cause this connection to be broken by the element 38 engaging the element 36, as in the case where magneto ignition is used instead of battery 20 ignition for starting purposes. In such a case the controlling circuit is opened in normal operation and closed during the stopping period to thereby short circuit the magneto.

Although I have shown my electric controlling apparatus adapted to be mounted 25 on the front of a board, with the terminal screws adapted to extend through the board and connections made at the back thereof, yet if desired, the controller can be mounted 30 on the back of the board and the element 14 extended so as to pass through the board and have only the wing-nut 14^a exposed on the front of the board; and the leads of course would be connected to the device at 35 the back of the board. The device may be located at the back of the board with the element 14 extended forwardly from the cover plate 3, or the device may be reversed and mounted on the back of the board and 40 the element 14 extended through the base plate of the device and through the board with a space provided for making the connections between the back of the board and the back of the controlling device. In this 45 case the direction of movement of the wing-nut and element 14 will be reversed as regards starting and stopping from that above described.

My invention is capable of undergoing 50 various other modifications to suit the requirements in any particular case and which need not be particularly referred to.

I claim:

1. The combination of a dynamo, battery, 55 gas engine, and an electric controller therefor, comprising a base plate, terminals carried thereby, a manually operated main switch carried by said base plate for closing and opening a circuit including the dynamo and battery, a manually operated ignition switch carried by said base plate, a cover plate, an electromagnetic device carried by said cover plate for automatically closing and opening the circuit between the dynamo and battery.

2. The combination of a dynamo, battery, gas engine, and an electric controller therefor, comprising a base plate, terminals carried thereby, a manually operated main switch carried by said base plate for closing and opening a circuit including the dynamo and battery, a manually operated ignition switch carried by said base plate, a cover plate, and an electromagnetic device carried by said cover plate for automatically closing and opening the circuit between the dynamo and battery, said electromagnetic device also automatically controlling said ignition switch. 70 75

3. The combination of a dynamo, battery, gas engine, and an electric controller therefor, comprising a base plate, terminals carried thereby, a manually operated main switch carried by said base plate for closing and opening a circuit including the dynamo and battery, a manually operated ignition switch carried by said base plate, a cover plate, and an electromagnetic device carried by said cover plate for automatically closing and opening the circuit between the dynamo and battery, said main switch and ignition switch being controlled by a single manually operated element. 80 85 90

4. The combination of a dynamo, battery, gas engine, and an electric controller therefor, comprising a base plate, terminals carried thereby, a manually operated main switch carried by said base plate for closing and opening a circuit including the dynamo and battery, a manually operated ignition switch carried by said base plate, a cover plate, and an electromagnetic device carried by said cover plate for automatically closing and opening the circuit between the dynamo and battery, said main switch and ignition switch being controlled by a single manually operated element for closing said main switch and for causing the ignition circuit to be effective by control of said ignition switch. 95 100 105 110

5. The combination of a dynamo, battery, gas engine, and an electric controller therefor, comprising a base plate, terminals carried thereby, a manually operated main switch carried by said base plate for closing and opening a circuit including the dynamo and battery, a manually operated ignition switch carried by said base plate, a cover plate, and an electromagnetic device carried by said cover plate for automatically closing and opening the circuit between the dynamo and battery, said main switch and ignition switch being controlled by a single manually operated element for closing said main switch and for causing the ignition circuit to be effective by control of said ignition switch and for also causing the ignition circuit to be rendered ineffective by control of said ignition switch. 115 120 125

FREDERIC HENRY BULLINGER.
